(57) **CLAIM**

The ornamental design for a track mounting assembly for a luminaire, as shown and described.

DESCRIPTION

FIG. 1 is a perspective view of a track mounting assembly for a luminaire showing our design;

FIG. 2 is a side elevational view thereof, where the opposite side elevational view is a mirror image of this view, and, therefore, has been omitted;

FIG. 3 is also a side elevational view thereof, but wherein the luminaire (shown by broken line representation) has a different orientation;

FIG. 4 is a front elevational view thereof, where the rear elevational view is a mirror image of this view and, therefore, has been omitted; and,

FIG. 5 is a bottom plan view thereof;

The broken line showing of environmental structure is for illustrative purposes only and forms no part of the claimed design.
